UNITED STATES PATENT OFFICE.

JOHN A. PARKINSON, OF SIOUX CITY, IOWA.

MOTOR-STARTER.

1,141,261.

Specification of Letters Patent.

Patented June 1, 1915.

Application filed September 24, 1913. Serial No. 791,663.

To all whom it may concern:

Be it known that I, JOHN A. PARKINSON, a citizen of the United States, and a resident of Sioux City, in the county of Woodbury and State of Iowa, have invented certain new and useful Improvements in Motor-Starters, of which the following is a specification.

This invention relates to means for starting explosive engines and more particularly to that class of engines employed for driving vehicles.

The invention has for its primary object the production of an improved and purely mechanical device with which the operator can readily start the engine without alighting from the vehicle.

Another object of the invention is the production of a device of this class inexpensive in both construction and maintenance and which may be applied to the great majority of motor-driven vehicles.

A further object is the construction of a motor-starter which may be employed in connection with the usual starting-crank.

A still further object is the provision in a device of this class of an improved means of control.

With these and other objects in view, the invention, consisting in the construction, combination and novel arrangement of parts, will be fully understood from the following description, reference being had to the accompanying drawings forming a part of this application and in which like characters of reference indicate corresponding parts throughout the several views, of which, —

Figure 1 is a fragmentary front elevation of an automobile chassis equipped with the preferred embodiment of my invention; Fig. 2 is a plan view of the same; Fig. 3 is a side elevation of the hand-lever secured to the dash, the lever handle being omitted; Fig. 4 is an enlarged plan view of the preferred form of my device with hand-lever and connecting link omitted; Fig. 5 is a front elevation of the same with parts cut away to reveal the internal characteristics; Fig. 6 is a vertical section taken on the line 6—6 of Fig. 5 and mounted on the shaft and crank; Fig. 7 is a rear elevation of the operating lever with attached parts broken away; and Fig. 8 is a side elevation of the same.

Although I have herein presented the preferred embodiment of my invention, I would

not be understood as being limited to the specific form selected for illustration, for without departing from the spirit and scope of my invention, the device may be modified in various ways to suit the divers types of vehicles with which it may be used.

The invention contemplates, broadly, a ratchet mechanism mounted on the main shaft of the engine and actuated by a retractable lever and pawl mechanism controlled by a hand-lever operated from the driver's seat; and ratchet mechanism mounted on the starting-crank and engageable with said first ratchet mechanism, all of which will presently be made clear.

Referring now to the illustrations, 9 is an automobile frame, or chassis, equipped with the usual engine, 10, and dash, 11. The main shaft is represented at 12 and the familiar starting-crank at 13. The usual connection between the latter members, however, is supplanted by my novel device.

14 is a ratchet-wheel carried by the main-shaft and preferably cast integrally with the belt pulley, 15, secured upon the shaft by a cross-pin, 16, which pulley is generally employed to drive the radiator fan. The ratchet-wheel, 14, encircles a second ratchet-wheel, 17, secured by a cross-pin, 18, or otherwise, upon the starting-crank, 13. In the front side of the ratchet-wheel, 14, are depressions, 19, within which are dogs, 20, pivoted upon pins, 21, carried by the ratchet, which dogs are adapted for engagement with the internal ratchet-wheel.

By virtue of this construction it is clear that when necessary to spin the main-shaft in order to start the engine, which is frequently required in cold weather, the crank may still be used. When the engine is at rest one or more of the dogs 20 will be in position for engagement with the ratchet-wheel, 17, whereupon rotation of the crank will impart like movement to the main-shaft; and after the engine has started to run automatically the dogs are thrown outwardly and freed from the internal ratchet-wheel by centrifugal force. By providing several teeth on the internal ratchet, as shown, the crank may always be engaged at a convenient point to obtain a purchase.

22 is a lever the inner end of which is formed in a collar, 23, free to turn upon the hub of the internal ratchet-wheel, and the outer end is off-set rearwardly and terminates in a segment concentric with the collar

and provided with a peripheral groove, 24, within which lies a flexible link, 25, one end of which is secured to a cross-pin, 26, extending through the lever. The said flexible link passes over a direction pulley, 27, secured to the chassis, and is then secured to an arm, 28, extending laterally from an upright shaft, 29, journaled in suitable bearings, 30, on the rear side of the dash. A horizontal hand-lever, 31, provided on the upright shaft, rests normally within a U-shaped socket, 32, mounted upon the dash and the arms of which tend to spring toward each other and thereby reduce the shock incident to the retraction of the lever.

A retractable spring, 33, secured to the chassis and connected by a link, 34, with the lever, 22, serves to maintain the latter in normal position and retract the same and the hand-lever after operation.

On the rear side of the lever, 22, is a pawl, 35, fulcrumed at 36, and provided with a heel, 37, which is forwardly off-set to engage the lower edge of the lever, and due to the tension of the retractable means, 33, normally engages a fixed member, 38, which may be a portion of the frame of the vehicle as illustrated, and by virtue of which the pawl is normally held out of engagement with the ratchet 14.

Although the pawl is so balanced that it will engage the ratchet when the lever is lifted, I prefer to employ means whereby the engagement is quicker and more positive. For this purpose a post, 39, pivotally-secured to the pawl, as at 41, extends through the off-set segment, into the groove thereof and engages the flexible link. A compression-spring 40, interposed between the segment and the pawl and encircling the post, tends to force the pawl toward the ratchet-wheel. However, when constructed with the post extending into the groove, as illustrated in Fig. 5, the presence of the compression-spring is arbitrary, for when the hand-lever is moved to impart strain on the flexible link, the latter will coat with the post to engage the pawl and ratchet-wheel.

From the structure now disclosed it is clear that the operator may start the engine by drawing the hand-lever toward him whereupon the lever 22 and attached pawl will turn the ratchet-wheel, 14, in the desired direction. When the hand-lever is released it is retracted by the lever 22.

The specific hand-lever mechanism disclosed herein forms the subject-matter of my divisional application, 848,674, filed July 2, 1914.

Having thus described my invention what I claim as new and desire to secure by Letters Patent is,—

1. A device of the class described comprising in combination with the main-shaft

and starting-crank, a ratchet-wheel mounted upon the main-shaft; a retractable lever fulcrumed coaxially with said ratchet-wheel; a pawl pivoted on said lever to engage said ratchet-wheel, said pawl having a portion engageable by a stop whereby it is normally disengaged from said ratchet-wheel; a hand-lever fulcrumed upon the dash; a flexible link between said levers; a second ratchet-wheel mounted upon the starting-crank; and dogs upon the said first ratchet-wheel adapted to engage said second ratchet-wheel and be thrown outwardly therefrom by centrifugal force.

2. A device of the class described comprising in combination with the main-shaft and starting-crank, a ratchet-wheel mounted upon the main-shaft; a ratchet-wheel mounted on the starting-crank; dogs pivoted on said first ratchet-wheel and engageable by said second ratchet-wheel; a retractable lever fulcrumed coaxially with said ratchet-wheels and having its outer end off-set and arched concentric with the fulcrum and provided with a peripheral groove; a pawl pivoted on said lever to engage said first ratchet-wheel, said pawl having a portion engageable by a stop whereby it is normally disengaged from the ratchet-wheel; a post pivoted to said pawl and extended into said groove; a hand-lever fulcrumed upon the dash; a flexible link between said hand-lever and the first said lever, said link being disposed within said groove and adapted, when traction is made upon it, to force said post inwardly.

3. A device of the class described comprising in combination with the main-shaft and starting-crank, a ratchet-wheel mounted upon the main-shaft and provided with depressions in one side thereof; dogs pivoted within said depressions; a ratchet-wheel having a hub mounted upon the starting-crank, encircled by said first ratchet-wheel and adapted for engagement with the dogs; a retractable lever integral with a collar freely mounted on the hub of said second ratchet-wheel, said lever having a pawl pivoted thereon for engagement with said first ratchet-wheel; and a flexible link secured to said lever and terminating upon a hand-lever controlled from the driver's seat.

4. A device of the class described comprising in combination with the main-shaft, starting-crank, and a ratchet-wheel mounted on the main-shaft and having depressions in one side thereof, dogs pivoted in said depressions; a ratchet-wheel having a hub mounted upon the starting-crank, encircled by said first ratchet-wheel and adapted for engagement with said dogs; a retractable lever mounted freely upon the hub of said second ratchet-wheel and provided with a pawl for engagement with said first ratchet-wheel, a stop to normally disengage

said pawl from said ratchet-wheel; and means for operating said lever comprising a hand-lever pivoted upon the dash and a flexible link between said hand-lever and a first named lever.

5. In a motor-starter a ratchet-wheel mounted upon the main-shaft and provided with depressions in one side thereof, dogs pivoted within said depressions, and a 10 ratchet-wheel having a hub mounted upon the starting-shaft and adapted for engagement with said dogs, in combination with a ratchetable lever having an integral collar mounted freely upon the hub of the second 15 said ratchet-wheel, said lever being off-set rearwardly and terminating in a segment pivoted upon said lever to engage said first

ratchet-wheel, said pawl having a heel offset forwardly below the lever, a stop to normally engage said heel and disengage the pawl from said first ratchet-wheel, a post secured to said pawl and extended into the off-set portion of the lever; a flexible link secured to said lever and within the groove; 20 and means for imparting traction to said flexible link controlled from the driver's seat.

In testimony whereof I have hereunto set my hand, in the presence of two subscribing 25 witnesses,

JOHN A. PARKINSON.
